UNITED STATES PATENT OFFICE.

HENRY F. GOETZ, OF WATERBURY, CONNECTICUT, ASSIGNOR TO WATERBURY MFG. CO., OF WATERBURY, CONNECTICUT, A CORPORATION.

BATH AND BASIN WASTE.

1,111,375.

Specification of Letters Patent.

Patented Sept. 22, 1914.

Application filed July 16, 1914. Serial No. 851,320.

To all whom it may concern:

Be it known that I, HENRY F. GOETZ, a citizen of the United States, residing at Waterbury, in the county of New Haven and State of Connecticut, have invented a new and useful Improvement in Bath and Basin Wastes; and I do hereby declare the following, when taken in connection with the accompanying drawings and the characters of reference marked thereon, to be a full, clear, and exact description of the same, and which said drawings constitute part of this application, and represent, in—

Figure 1 a sectional view of a bath or basin waste constructed in accordance with my invention, and shown in the closed position. Fig. 2 a side view partly in section with the valve in the open position. Fig. 3 a top or plan view. Fig. 4 an underside view of the bonnet and the flange supported thereby detached. Fig. 5 a top or plan view of the valve stem detached. Fig. 6 a sectional view on the line *a—b* of Fig. 1. Fig. 7 a sectional view on the line *c—d* of Fig. 1. This invention relates to an improvement in bath and basin wastes, the object being to provide a waste which may be locked in the open position and spring pressed to its closed position, so that the closing movement is practically automatic; and the invention consists in the construction hereinafter described and particularly recited in the claims.

In carrying out my invention, I employ an outer tube 2 which is adapted to be connected with a basin slab or the side of a bath tub to which it is attached at the upper end in substantially the usual manner, and this tube extends into a casing 3 which also connects in the usual manner with a pipe 4 to the bottom of the basin or tub and also by a pipe 5 with the waste pipe. This casing 3 is provided at its lower end where it opens into the waste pipe 5 with a seat 6 which is adapted to receive a tubular valve 7 the inner end 8 of which is beveled to closely fit the seat 6. This tubular valve 7 is adjustably connected with a tubular valve stem 9 which is formed near its upper end on opposite sides with cam slots 10 and 11 into which a pin 12 projects, this pin being mounted in the lower end of a spindle 13 which is provided at its upper end with an operating handle 14. The upper end of the valve stem 9 is closed by a plate 15. The up-

per end of the tube 2 is coupled with a bonnet 16 of larger diameter than the diameter of the tube, and this bonnet supports a flange 17 which extends downward into the tube and is formed on opposite sides with inwardly projecting fingers 21 which enter vertically arranged slots 22 on opposite sides of the valve stem 9 and by which the upper end of the valve stem is guided. The bonnet also forms a bearing for the upper end of the spindle 13. Between the plate 15 and the bonnet 16 and surrounding the spindle 13 is a spring 18. The valve stem is also provided near its upper end with overflow openings 19. As shown in Fig. 1 of the drawings the waste is closed; that is to say, the end 8 of the valve 7 rests upon the seat 6 and consequently closes the upper end of the waste pipe 5, and this valve is held in its down position by the pressure of the spring 18 bearing upon the upper end of the valve stem 9. To open the valve the handle 14 is turned in one direction or the other causing the pin 12 to move in the cam slots 10 and 11 so as to raise the valve stem 9 against the pressure of the spring 18 and lifts the valve 7 away from the seat 6 so as to open the upper end of the waste pipe 5. As the handle 14 completes its movement, the pin enters the straight portion of the slots 10 and 11 and thereby locks the valve stem in its raised position. Preferably the pin 12 will correspond substantially in diameter to the internal diameter of the tube 2 so as to form a guide for the upper end of the valve stem and preferably the locking collar 20 which locks the valve 7 with the stem 9 is in the form of a spider as shown in Fig. 6, the ends of which co-acting with the inner walls of the tube, form a guide for the lower end of the valve stem.

I thus provide in a very simple form a waste for baths and basins which when released will spring downward to close the waste and which may be locked in its raised or open position.

I claim:—

1. A bath or basin waste comprising a tube, a casing coupled with the lower end of said tube, said casing formed with a valve seat, a valve adapted to co-act with said seat, a tubular valve stem coupled with said valve, said valve stem formed with cam slots, a rotatable spindle, a pin carried by the spindle and entering said cam slots, and a spring 119

bearing upon the upper end of the valve stem and tending to force the valve to its seat.

2. A bath or basin waste comprising a tube, a casing coupled with the lower end of said tube, said casing formed with a valve seat, a tubular valve the lower end of which co-acts with said seat, a tubular valve stem with which the tubular valve is connected, said valve stem formed on opposite sides with cam slots, a bonnet connected with the upper end of the tube and adapted to support said tube, a flange also supported by

the bonnet and adapted to guide the upper end of said valve stem, a rotatable spindle 15 extending through said bonnet, a pin carried by the lower end of said spindle and engaging with said cam slots, and means for turning said spindle.

In testimony whereof, I have signed this specification in the presence of two subscribing witnesses.

HENRY F. GOETZ.
